LOCKING AND CLEANING COKE OVEN
DOOR

Carl Otto, Essen, and Eberhard Grasshoff, Bochum, Germany; said Grasshoff, assignor, by mesne assignments, to the firm Otto-Wilputte Ovenbouw Maatschappij N. V., The Hague, Netherlands, a corporation of the Netherlands, and said Otto, assignor to Fuel Refining Corporation, Dover, Del., a corporation of Delaware

Application December 8, 1937, Serial No. 178,706
In Germany December 28, 1936

12 Claims. (Cl. 202—248)

The general object of the present invention is to provide an improved self-sealing coke oven door especially adapted for use in a horizontal coking oven. More specifically, the object of the invention is to provide a coke oven door including spring means which limit and determine the sealing pressure with which sealing edge of the usual flexible sealing means carried by the door bears against the cooperating sealing surface of the doorway when the door is locked in its closed position, and which are so associated with door locking means that the door may be automatically locked and released by respective down and up movements given the rigid outer portion of the door whereby the door locking and releasing operations may be effected by the action of a simple door machine having any usual or suitable means for engaging the door to raise and lower the latter during the door removing and replacing operations.

In each door unlocking and removing operation, and in each door closing and locking operation, the sealing edge of the flexible sealing means carried by the door is moved parallel to the door frame sealing surface while being pressed firmly against said surface, whereby said surface and sealing edge coact to clean each other. This cleaning action insures a gas-tight joint in the locked condition of the closure under conditions in which the joint would be leaky if the parts were not cleaned.

Our invention in its preferred forms, comprises special provisions for augmenting the extent and effectiveness of the above described sealing action, and includes provisions for strengthening the sealing edge portion of the flexible sealing element to resist the stresses to which it is subjected during the cleaning action, without significantly impairing the desired flexibility of the sealing edge in a direction perpendicular to the sealing surface.

For a better understanding of the invention, its advantages and specific objects attained with it, reference should be had to the accompanying drawing and descriptive matter in which we have illustrated and described preferred embodiments of our invention.

Of the drawing:

Fig. 1 is a partial vertical section of a coke oven battery, taken on the line 1—1 of Fig. 2;

Fig. 2 is a horizontal section on the line 2—2 of Fig. 1;

Fig. 3 is an elevation of a portion of the coke oven door and door frame shown in Figs. 1 and 2,

on a plane parallel to the plane of the section shown in Fig. 1;

Fig. 4 is an elevation illustrating a modification of the retaining hook shown in Fig. 3;

Figs. 5 and 6 are diagrammatic elevations, at right angles to Fig. 1, of door carried sealing elements differing in form from one another and from the sealing elements shown in Figs. 1 and 2; and

Fig. 7 is a perspective view of a portion of a sealing member having special rim strengthening provisions.

In the drawing we have illustrated the use of the present invention in a coke oven door and door frame construction of known type, except in respect to the special resilient pressure and locking means provided in accordance with the present invention. The coke oven door illustrated, comprises a rigid outer frame or supporting section, a flexible sealing member and an inner plug section. Said outer section includes main vertical channel bar members 1, and horizontal connections between said members, including one such connection 15, associated with each of the two locking bars 7, as hereinafter described. The sealing member comprises a flexible metal plate 2, extending across the doorway and supporting a marginal rim or sealing edge portion 3, extending transversely to the plate 2 and adapted to engage and make a gas-tight joint with a sealing surface 4' on a door frame member 4, which surrounds the mouth of the oven chamber, with which the door is associated. The outer door section supports the flexible sealing member of the door through connecting means which need not be illustrated or described since they may be of known form, such, for example, as that shown in the Otto U. S. Patent 1,827,329. The brick work 6 of the plug section of the door, rests upon a supporting metallic shoe 5, which may be connected in a known manner to, and is directly supported by the sealing member 2.

The door shown in Figs. 1—3, is locked in its closed position by upper and lower locking bars 7. In the closed and locked condition of the door, each bar 7 has each end in engagement as shown in Fig. 3, with the inclined surface 8' or inner edge of the uprising hook portion of a corresponding door retaining hook member 8. The hook members 8 are secured to the door-frame member at the opposite sides of the doorway in position for engagement by the ends of the two locking bars. In the construction illustrated, each locking bar 7 has an anti-friction 55

roller revolvably mounted on each of its ends, for rolling engagement with the corresponding edge 3'. Each locking bar 7 is mounted on a corresponding support comprising a bolt 10 extending in the axial direction of the door, midway between the sides of the latter, and comprising a supporting body or cross head 11 mounted for sliding movement in the axial direction of the door, in a guideway 14 formed in the corresponding horizontal part 15, extending between and connecting the channels 1.

The bolt 10 is in threaded engagement with the cross head 11 and has its outer end 12 square for wrench engagement. By varying the extent to which the bolt 10 is screwed into the cross head 11, the effective length of the locking bar support may be varied. A spring 13 acts between the inner end of the cross head 11 and the member 15 in the direction tending to move the locking bar outwardly away from the sealing member of the door, and from the sealing surface 4' which it normally engages. A bolt 13' may be extended axially through each spring 13 to form a connection between each part 15 and the corresponding cross head 11, limiting its outward movement in its guide head 14, when the locking bar is not in engagement with the corresponding hook members 8. Each bolt 10 extends through, and is so mounted on the corresponding locking bar 7, that the bolt may be rotated relative to the bar, but is not movable relative to the latter in the direction of its length. As shown, there is a spline connection comprising a screw 15' between each cross head part 11 and guide member 15. As shown also, lugs or projections 16 secured to the channel bars 1, prevent turning movement of the locking bars about the axis of its supporting bolt 10. Adjustable clamping connections 17, of any usual or suitable form, may be provided between the rigid outer section of the door and the flexible sealing member engaging the latter adjacent the margin of the plate 2, to bend the sealing member as required to make the contour of its sealing edge conform to the shape of the sealing surface 4'.

In the normal contemplated operation, with the door of Figs. 1-3 in its closed and locked position shown in Figs. 1, 2, 3, the force with which each sealing bar presses outwardly against the edges 3' of the two corresponding retaining hook members 8, is determined by and equal to the compression force to which the corresponding spring 13 is then subjected. The compression forces to which the two springs 13 of each door are subjected collectively determine the sealing pressure between the door frame 4 and sealing rim or edge 3 of the door. The compression force to which each spring 13 is then subjected and thereby the sealing pressure, may be adjusted by varying the extent to which the corresponding bolt 10 is screwed into the corresponding cross head or support 11. The door may be moved out of its closed and locked position shown in Figs. 1, 2, and 3, by an upwardly acting force impressed upon the rigid outer section of the door by a vertically movable door machine arm or lifting element 18, which in its upward movement engages a lifting shoulder or part 19 provided for the purpose on the rigid outer section of the door.

As the door machine raises the door from its closed position, in which the weight of the door is sustained by the door frame 4, the sealing edge portion 3 of the sealing member is moved along the sealing surface 4' of the door frame 4, while 75 pressed against the latter by the springs 13.

While owing to the inclination of the edges 3', the pressure between the sealing edge and door frame sealing surface will progressively diminish as the door is raised sufficiently to permit the rollers 9 to clear the upper ends of the hook portion of the member 8, nevertheless, during the initial portion of the door removing, and the final portion of the door replacing operation, the said pressure is adequate to subject sealing surface 4' and edge 3 to substantial cleaning action.

To augment the cleaning action, the retaining members 8 of the construction first described may be replaced by the retaining members 8a shown in Fig. 4. As shown, the latter differ from 15 the retaining member 8 only in that the inner edge of the uprising hook portion of each member 8a, comprises a vertical portion H'' below, and into which the inclined edge portion H' emerges. The vertical edge portions 8'' are so 20 disposed that in the closed and locked position, portion 8'' is engaged by the roller 9 at the corresponding locking bar end, at an appreciable distance below the lower end of the inclined edge portions 8'. The vertical movement of the door, occurring while the locking bars are in operative engagement with the hook edge portions 8'', result in movement of the sealing 3 along the sealing surface 4', while said edge is pressed against said surface with the full sealing pressure. If 30 desirable, the cleaning action due to the vertical movement of the door may be supplemented by a horizontal movement of the door in a direction parallel to the sealing surface 4'. Such movement may be given to the door by any ordinary 35 door machine having provisions for effecting its movement in the direction of the length of the battery.

To give the sealing member additional capacity to resist distortion by the stresses to which it is subjected when the door is moved vertically with its sealing edge 3 pressed against the sealing surface 4' as above described, in lieu of a sealing member 2 having the usual rectangular outline, we may employ the special sealing member form 2a 45 shown in Fig. 5, in which the upper and lower end portions 3a of the flat sealing plate and the adjacent rim portions are of rounded arch form shown in Fig. 5, or may employ a sealing member 2b, having its end portions 3b of the different 50 arch form shown in Fig. 6. Alternatively, or additionally, the end portions and, if desired, the side portion also, of the sealing rim, and the marginal portion of the plate 2, may be strengthened by reinforcing web parts 20 welded to the sealing rim 3 at the corners of the latter, and each welded both to the rim 3 and to the plate 2, the plane of each part 21 being perpendicular to the adjacent portion of the rim 3 and to the body plate 2.

As will be apparent to those skilled in the art, the invention is characterized, by the advantageous cleaning action provided, and by the inherent mechanical simplicity and effectiveness of the resilient sealing pressure and locking means provided, and also by the capacity of the door to be moved into and out of its closed and locked position, by a door machine having only such door lifting and lowering provisions as are commonly provided for removing and replacing coke 70 oven doors having manually operable locking means.

As those skilled in the art will understand, changes may be made in the form of the apparatus disclosed without departing from the 75

spirit of our invention as set forth in the appended claims and in some cases, use may be made of certain features without corresponding use of other features.

5 Having now described our invention, what we claim as new and desire to secure by Letters Patent, is:

1. A coke oven door adapted to close a doorway in a coke oven structure having a door seat surrounding said doorway, and having door holding means comprising a surface in front of and inclined upwardly and away from said seat, said door comprising seat engaging means, a locking member mounted on said door at its outer side to 10 move toward and away from the door and adapted to engage said surface, and be thereby given movement toward said door when said door is lowered into its closed position, and resilient means acting between said locking member 15 and door and opposing said movement of the locking member toward said door, and thereby forcing said seat engaging means against said seat, as said door is lowered into its closed position.

25 2. A self-sealing coke oven door adapted to close a doorway in a coke oven structure having a sealing surface surrounding said doorway, and having door holding means comprising a surface in front of and inclined upwardly and away from 30 said surface, said door comprising a flexible sealing member adapted to engage said sealing surface, a locking member mounted on said door at its outer side to move toward and away from the door and adapted to engage said inclined surface, and be thereby given movement toward said door when the latter is lowered into its closed position, and resilient means acting between said locking member and door, and opposing movement of 35 said locking member toward said door and thereby forcing said sealing member against said sealing surface as said door is lowered into its closed position.

3. A coke oven door as specified in claim 1, in which said locking member is mounted on a support 45 extending and movable in a direction parallel to the door axis and adjustable in length, and forming a strut interposed in series with said resilient means between said door and locking member.

50 4. A coke oven door as specified in claim 1, in which said locking means is a locking bar with rollers journaled on its ends and each adapted to engage portions of inclined surface at opposite sides of the door.

55 5. The combination with a horizontal coke oven structure having a horizontal doorway and a sealing surface surrounding said doorway and substantially perpendicular to the axis thereof and having uprising hooks at the opposite sides of

60 the door, each of said hooks having a lower portion of its edge adjacent said surface substantially parallel to the latter, and having an upper edge portion inclined upwardly and outwardly from said lower edge portion, and a self-sealing coke oven door adapted to be lowered into position to 65 close said doorway and comprising a door body, flexible sealing means supported by said body and engaging said sealing surface in the closed position of the door, a locking bar mounted on said

70 body to move toward and away from the latter and adapted to engage said hooks and move downwardly along their inclined upper edge portions during an initial portion and to move downwardly along the said lower portions of the hook edges, as the door is being lowered into its

closed position, and resilient means supported by said body and acting between the latter and said bar and adapted to press said sealing means inwardly against said surface and to press said locking bar outwardly against said hooks when said locking bar is between said surface and said hooks.

5 6. In the operation of a horizontal coke oven having a substantially vertical metallic sealing surface surrounding a doorway at the end of an oven chamber, and having a plug door normally closing said doorway and comprising a refractory plug body extending into and sufficiently smaller than said doorway in cross section to adapt it for a limited movement in said doorway 10 in a direction parallel to said surface, and having flexible sealing means including a sheet metal part extending perpendicularly to said surface with its edge in engagement therewith when the door is in the closed position, the method of cleaning said edge and surface which consists in moving the door relative to the doorway in a direction parallel to said surface while impressing a yielding force on said sheet metal part and thereby pressing the edge of said part against said surface.

15 7. In a combination a horizontal coke oven structure having a substantially vertical sealing surface surrounding a doorway at the end of an oven chamber, a self-sealing plug door normally closing said doorway and comprising a refractory body extending into and substantially filling the doorway when the door is in its closed position, but of somewhat less vertical extent than said doorway to permit of a limited vertical movement 20 of the door in said doorway toward and away from a lower closed position of the door, said door comprising flexible sealing means including a sheet metal part adapted to extend perpendicularly to said surface with its edge in engagement therewith and means for releasably connecting said structure and door to hold the latter in its closed position and adapted to subject said door to a resilient force pressing said edge against said surface when said door is in its closed position 25 and while moving vertically toward and away from its closed position.

30 8. In combination a horizontal coke oven structure having a substantially vertical sealing surface surrounding a doorway at the end of an oven chamber, a self-sealing plug door normally closing said doorway and comprising a refractory body extending into and substantially filling the doorway when the door is in its closed position, but of somewhat less vertical extent than 35 said doorway to permit of a limited vertical movement of the door in said doorway down into, and up out of a lower closed position and, said door comprising flexible sealing means including a sheet metal part adapted to extend perpendicularly to said surface with its edge in engagement therewith and means for releasably connecting said structure and door to hold the latter in its closed position and adapted to subject said door to a resilient force pressing said edge against said 40 surface when said door is in its closed position and while moving vertically toward and away from its closed position, said sealing means having upper and lower end portions of arch form, whereby said portions are strengthened to resist 45 stresses tending to incline said part to said surface.

50 9. In combination a horizontal coke oven structure having a substantially vertical sealing surface surrounding a doorway at the end of an 55

70 75

oven chamber, a self-sealing plug door normally closing said doorway and comprising a refractory body extending into and substantially filling the doorway when the door is in its closed position, but of somewhat less vertical extent than said doorway to permit of a limited vertical movement of said door in said doorway down into and up out of a lower closed position, said door comprising flexible sealing means including a sheet metal part adapted to extend perpendicularly to said surface with its edge in engagement therewith, means for releasably connecting said structure and door to hold the latter in its closed position and adapted to subject said door to a resilient force pressing said edge against said surface when said door is in its closed position and while moving vertically toward and away from its closed position and reinforcing parts secured to the said sheet metal part and stiffening the latter against bending movement about an axis parallel to said surface when said part is in engagement with said surface.

10. The combination with a coke oven structure having a door seat and door holding means having a surface in front of and inclined upwardly and away from said seat, of a self-sealing coke oven door comprising a body and flexible sealing means supported by said body and adapted to be lowered into its closed position with said sealing means in engagement with said seat, a locking member mounted on said door body for movements toward and away from the latter, and resilient means acting between said door and locking

member and tending to move the latter away from said door, said locking member being adapted to engage said surface and move downwardly along the latter as the door is lowered into its closed position to thereby compress said spring and force the door against its seat. 5

11. A combination as specified in claim 10, in which said holding means has a surface below said inclined surface and parallel to said seat, and adapted to be engaged by said door in a final 10 portion of the lowering movement of the door into its closed position.

12. In a self-sealing coke oven door, the combination with a plug section of refractory material, a sealing member at the outer side of said 15 plug section and comprising a substantially flat, flexible, metal plate, a thin flexible metallic sealing rim extending perpendicularly away from the inner side of said plate adjacent the margin of the latter and surrounding and spaced away from the outer portion of said plug section and adapted to have its edge remote from the plate in sealing engagement with a coke oven door frame sealing surface surrounding a doorway into which said plug section extends and metal parts secured 20 to and connecting said rim and plate and extending transversely to said rim and plate and increasing the resistance of the rim to stresses tending to change its angle of inclination to said plate. 25
